CLAIM

We claim the ornamental design for a writing instrument, as shown and described.

DESCRIPTION

FIG. 1 is a perspective view of a writing instrument showing our new design;

FIG. 2 is front view of the same;

FIG. 3 is a rear view of the same;

FIG. 4 is a top view of the same;

FIG. 5 is a right side view of the same; and,

FIG. 6 is a left side view of the same.

Portions of the writing instrument shown in broken lines are for illustrative purposes only, and form no part of the claimed design.
